(No Model.)

H. D. EDWARDS.
ROLLER HARROW.

No. 596,147.

Patented Dec. 28, 1897.

UNITED STATES PATENT OFFICE.

HOUGHTON D. EDWARDS, OF HISEVILLE, KENTUCKY.

ROLLER-HARROW.

SPECIFICATION forming part of Letters Patent No. 596,147, dated December 28, 1897.

Application filed April 26, 1897. Serial No. 633,856. (No model.)

To all whom it may concern:

Be it known that I, HOUGHTON D. EDWARDS, a citizen of the United States, residing at Hiseville, in the county of Barren and State of Kentucky, have invented certain new and useful Improvements in Roller-Harrows; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to improvements in harrows of that class wherein the harrow-teeth are placed upon rollers or drums which are adapted to revolve when the harrow is drawn over the ground.

The objects of my invention are to provide a harrow of that class that will be simple in construction, that may be adjusted to various widths, and that will harrow the ground and at the same time crush the clods and roll the surface.

My invention consists in the construction and combination of parts shown in the accompanying drawings and described in the following specification.

In the drawings, Figure 1 is a top plan view. Fig. 2 is a side elevation. Fig. 3 is a front view of the frame with the rollers removed. Fig. 4 shows the pivoted brace-rod both connected and disconnected, and Fig. 5 is an edge view of one of the journals whereby the front ends of the rollers are secured to the frame.

The frame, which is V-shaped in outline, consists of a central piece A and the side pieces B, which are secured at the forward ends to the sides of the center piece A near the front by means of the hinges C. The center piece A is provided with a clevis h at its front end, to which horses may be attached or hitched, and near the rear end are a series of openings i, which receive the pin j. The center and side pieces are secured together at their rear ends by means of a pivoted brace-rod formed in two sections D and E, which are pivotally connected in the center by a bolt or rivet k. The outer ends of the rod have openings adapted to receive bolts l,

whereby said outer ends are each secured to the side pieces B, and the inner ends of each section have the openings m to receive the bolt k, and in addition thereto the section D 55 is provided with a shoulder n, having an opening o, which is adapted to receive the pin j and thereby connect the brace-rod at the desired point with the center piece A. It will be seen that the distance between the rear ends r of the side pieces B may be increased by removing the pin j, drawing the pivoted rod back on the center piece A, and again placing the pin in the openings o and i 60 in the brace-rod and center piece at the desired point. To the side pieces B are secured the front and rear depending roller-journals F and G, the front journals F being formed with angles s for the purpose of throwing the journal-bearings under the side pieces B 65 and thereby bringing the front ends of the rollers close together, so as to prevent leaving an open space in the center.

The rollers H are slightly cone-shaped with the small end in front and are provided with 75 metal bands t at proper intervals throughout their length, to which the harrow-teeth v are suitably secured. A journal d in the front and rear ends of the rollers H enters the bearings e in the lower ends of the depending 80 roller-journals F and G. When the harrow is drawn over the ground, the rollers H revolve and the teeth v will harrow the ground, while the face of the rollers will crush the clods and roll the surface.

It is a well-known fact that the soil will retain moisture much better when the surface is somewhat packed than when loosely thrown up by the ordinary harrow. My improved harrow is designed to pack the earth slightly 90 and at the same time harrow it, thereby saving the time and labor of going over the ground again with a land-roller.

It will be understood that the ground will be more thoroughly harrowed when the rear 95 ends of the rollers are close together than when extended, and the pivoted brace-rod is provided for the purpose of adjusting the rollers to meet the requirements of the soil operated upon, as a loose soil needs less harrowing and more rolling, while a firm damp soil requires the reverse.

Having described my invention, what I claim, and desire to secure by Letters Patent of the United States, is—

1. In a harrow of the class described, the combination of the frame consisting of the center piece A, having openings i, the side pieces B, secured to the center piece A, by the hinges C, and provided with depending roller-journals F, and G, said side and center pieces being adjustably secured at their rear ends by means of the pivoted brace-rod consisting of the section D, having a shoulder n, with an opening o, to receive a pin j, and the section E, pivoted to section D; cone-shaped rollers H, having the bands t, to which are secured the harrow-teeth v, said rollers being provided with the journals d, which enter the bearings e, in the depending roller-journals F, and G, all substantially as shown and described.
2. The combination in a harrow having an adjustable frame, of the pivoted brace-rod consisting of two sections D, and E, the outer end of each section having an opening where-
25 by they are secured to the side pieces B, of the frames by the bolts l, the inner ends having the openings m, to receive the bolt k, and

the section D, having the shoulder n, with the opening o, said opening being adapted to receive a pin j, which lies therein and in one 30 of the openings i, in the center piece A, with said frame, and the conical rollers H, having the bands t, and the harrow-teeth v, secured thereto, said rollers being connected with the frame by means of the depending roller-jour- 35 nals, substantially as set forth.

3. A roller-harrow having a V-shaped adjustable frame consisting of the center piece A, and the side pieces B, secured to said center piece A, at their front ends by the hinges 40 C, and adjustably secured near their rear ends by the pivoted brace-rod formed as shown in two sections, with the cone-shaped rollers H, having journals d, connected with the frame by means of the depending roller-journals F, 45 and G, said rollers carrying bands t, to which are attached teeth v, as shown and described.

In testimony whereof I affix my signature in presence of two witnesses.

HOUGHTON D. EDWARDS.

Witnesses:

SOLON EDWARDS,
ARTHUR R. SCHOOLER.
